[57] CLAIM

The ornamental design for a data port coupler, as shown and described.

DESCRIPTION

FIG. 1 is a front perspective view of a data port coupler showing my new design;

FIG. 2 is a front elevational view thereof;

FIG. 3 is a right side elevational view thereof, the left side view being a mirror image of that shown;

FIG. 4 is a rear elevational view thereof;

FIG. 5 is a bottom plan view thereof, the top plan view being a mirror image of that shown;

FIG. 6 is a rear perspective view thereof;

FIG. 7 is another rear perspective view thereof showing the coupler use with alternative electrical connectors; and,

FIG. 8 is a perspective view of multiple data port couplers showing the use thereof.

The broken lines shown in FIGS. 3 through 8 are for illustrative purposes only and form no part of the claimed design.
